Fig. 10

FIG. 1 is a front elevational view of an embodiment of a combined switch plate and thermometer illustrating my new design;

FIG. 2 is a side elevational view of FIG. 1;

FIG. 3 is a back elevational view of FIG. 1;

FIG. 4 is a bottom view of the combined switch plate and thermometer of FIG. 1, the top view being a mirror image thereof;

FIG. 5 is a front elevational view of another embodiment;

FIG. 6 is a front elevational view of another embodiment;

FIG. 7 is a front elevation view of another embodiment;

FIG. 8 is a front elevational view of another embodiment;

FIG. 9 is a front elevational view of another embodiment;

FIG. 10 is a back elevational view of FIGS. 7-9;

FIG. 11 is a side elevational view of FIGS. 7-9; and

Fig. 11 Fig. 12

FIG. 12 is a top plan view of FIGS. 7-9, the bottom plan views being substantially identical to the top plan view of FIG. 12.

I claim:

The ornamental design for a combined switch plate and thermometer, as shown and described.
